UNITED STATES PATENT OFFICE

161,638

SHOESHINE BOX

John J. Mekalainas, Bronx, N. Y.

Application February 13, 1950, Serial No. 7,924

Term of patent 14 years

(Cl. D58—12.6)

To all whom it may concern:

Be it known that I, John J. Mekalainas, a citizen of the United States, residing at Bronx, Bronx County, State of New York, have invented a new, original, and ornamental design for Shoeshine Box, of which the following is a specification, reference being had to the accompanying drawing, forming a part hereof, in which:

I claim:

The ornamental design for a shoeshine box, substantially as shown.

JOHN J. MEKALAINAS.
